UNITED STATES PATENT OFFICE

WILLIAM R. MOORE, JR., OF HAGERSTOWN, MARYLAND, ASSIGNOR TO DECA-DISC PHONOGRAPH COMPANY, OF WAYNESBORO, PENNSYLVANIA, A CORPORATION OF PENNSYLVANIA

AUTOMATIC TALKING MACHINE

Application filed April 9, 1929. Serial No. 353,784.

This invention relates to improvements in automatic talking machines, and is an improvement over the machine shown in my Patent No. 1,800,803, granted April 14, 1931, for automatic talking machines. The invention consists in improved mechanism for playing records of different sizes, and for changing the records in order, to simplify the structure of the machine and to eliminate unnecessary noise during the changing of records.

Referring to the accompanying drawings, which are made a part hereof and on which similar reference characters indicate similar parts,

Figure 1 is a view in elevation of parts of a phonograph showing my improved record changing mechanism,

Figure 2 is a plan view of part of the mechanism for moving the phonograph tone arm into and out of playing position, and

Figure 3 is a view in elevation of one of the record supporting posts, together with the details of switch controlling means operated thereby.

The improvement in this application over the co-pending application above referred to consists in mechanism for selectively playing either a ten inch or a twelve inch record, using a single cam for moving the tone arm into and out of playing position. The improvement in the record changing mechanism consists in substituting a sliding sleeve or collar for the pawl and ratchet and spring operated mechanism in the above named application.

In the drawings numeral 10 indicates a portion of the table or bed forming a part of a cabinet of a phonograph of suitable design in which the upper end of a record changing cam shaft 11 is journaled, the lower end of the shaft being journaled in end brackets of a depending spider 12. The cam shaft 11 has supported on its lower end a cam 13 having a cam groove 14 of suitable contour and similar in most respects to the cam shown in the application referred to. Secured upon the upper end of the shaft 11 is a cam 15 which controls movement of the tone arm into and out of playing position. The mechanism for

moving the tone arm in and out as shown in detail in Fig. 2 comprises an arm 16 rigidly secured to the lower end of the tone arm 17. This arm 16 has in its outer end a pin 66 passing through and loosely fitting a slot 18 in a lever 19. The lever 19 is pivotally secured at 20 to a lever 21. The lever 21 is pivoted at 22 to any suitable support on the frame of the phonograph. A bracket 23 on the inner end of the lever 19 carries a roller 24 for engagement with the periphery of the cam 15. A lever 25 pivoted at 26 has an adjustable screw 27 threaded through its forward end, said screw engaging a leaf spring 28, which spring bears against the outer side 65 of the lever 19 substantially opposite the roller 24 on the other side. A spring 29 is secured to the rear end of the lever and at 30 to the frame work of the machine. The purpose of the spring 29 in co-operation with the spring 28 and the lever 26 is to hold the lever 19 so that the roller 24 will always be in engagement with the periphery of the cam 15, except in playing position, when the roller 24 is carried into the cut away position of 70 cam 15 by the advancement of the needle on the record. In this position the cam 15 and spring 29 are not exerting pressure against 75 23 being retarded by a stop 50 on the machine frame. The lever 21 is pivoted at 22 and is movable to either of two positions, its movement being limited by stops 31 and 32. Any suitable frictional securing means may be provided to hold the lever 21 against either of the stops 31 or 32. When in the position 80 shown in Fig. 2 the lever holds the pivot point 20 so as to position the cam follower 24 to play a large record, for example, a twelve inch record. When the lever 21 is swung to engage the stop 32 the pivot point 20 is moved 85 to the dotted line position shown at 33 in which position the cam follower roll is in position for playing a smaller record. A change of position from playing a ten inch to a twelve inch record therefore may be made by 90 a simple adjustment.

The structure for supporting the records is substantially that shown in Figure 14 in the patent referred to, and consists of posts 34 secured upon the table 10. These posts 100

are preferably substantially U-shaped in cross section. Pivoted to and within these posts are record supporting arms 35, these arms being positioned within standards 36. 5 The standards 36 are pivoted at 37 to the posts 34. These standards have rear notched portions 38 which have lugs 39 therethrough engageable by latches 40. The latches 40 are pivoted to levers 41. The upper ends of the 10 levers 41 have fingers 42 secured thereon for engagement between separate records 43. The fingers 42 are slightly resilient so that they will readily engage between records. The members 41 are pivoted to the posts 34. 15 To the lower end of one of the members 41 are secured bent arms 44 for operating switch setting devices shown as a whole at 45, and shown and described more fully in the patent. Within the standards 36 are pivotally mounted 20 the record supporting arms 35. These arms have depending ends 46 to which are secured springs 47, the springs being secured at their upper ends to the posts 34. The supporting arms 35 have rear hook like fingers 48 25 which normally rest against the under side of the latches 40. The supporting arms 35 are pivoted at 49 in slotted holes so as to permit slight vertical movement to the arms. When the record supporting table 51 is raised the 30 record posts 36 are pushed out radially. As they are pushed out, their lower ends are moved in and since the edge 39 engages the latch 40, the arms 41 are swung in so that the fingers 42 engage just above the lowermost 35 record on the post. As the record table engages the lowermost record, the fingers 42 prevent its rising. As soon as the record table is lowered and the weight of the records is received upon the posts 36 the record 40 arm 46 is moved down to its lowermost position bringing the edge 39 out of engagement with the lower part of the latch 40, which permits the latch to rest in its notch. As long as the record table is in its elevated position the 45 supports 36 will be held in their outermost radial position so as to keep the upper end of the arm 41 and consequently the fingers 42 in their innermost radial position. A pin 50' limits outward radial movement of the post 50 36.

The mechanism for moving the record table to change records comprises a sleeve 52 engaging the record table spindle 53. This sleeve has tensioning elements 54 by means of which 55 it may be so tightened as to engage the shaft 53 and support it in elevated position together with its load of records. A roller 55 is secured upon the upper end of the friction sleeve 52 this roller being adapted to travel 60 in the cam groove 14 on the cam 13. A stop member 56 may be secured on the frame of the machine in any suitable way, as for example, to a spider forming the lower end of the supporting means 12. The record changing 65 means just described operates as follows:

When the record changing mechanism has been set in motion the cam 13 revolves. The roller 55 traveling in the cam groove 14 raises the spindle 53 by means of the sleeve 52, the said sleeve 52 engaging the spindle with sufficient tightness to support the record table with its records. When the top of the table comes in engagement with the bottom of the lowermost record on the supports, the finger 42 has moved in above the lowermost record as described above, so that the record table cannot rise any higher. The sleeve 52 therefore must slide up on the spindle 53 a distance equal to the thickness of a record. As the cam 13 continues to rotate the sleeve 52 is brought down again to playing position. 70

When the record has been played and another record is to be taken upon the playing table the cam 13 is again caused to rotate. Upon starting its rotation the roller 55 will travel down into the valley 57 of the cam groove and in doing so will bring the lower end of the spindle 53 in engagement with the stop 56. This will cause the sleeve 52 to slide down the spindle a distance equal to the distance which it slid up before,—that is, a distance equal to the thickness of a record. Continued rotation of the cam 13 will carry the record table to its elevated position to receive an additional record. Since the sleeve 52 was slid down to its original starting position, it will now be forced to slide up the thickness of two records as the table takes a new record. Having received its record it will return to the playing elevation as before, and as it goes down into playing position it stops the playing surface of the record at the same horizontal level each time. This will continue until all the records have been played, the sleeve 52 sliding up each time a distance equal to the thickness of all the records on the table and sliding down the same distance at the end of a record. It will therefore readily be seen that when the finger 42 does not come out at the top after the tenth record has been played the whole ten records will be moved up and deposited upon the restoring or supporting arm 35. This is accomplished without any jar or clicking sound, due to the operation of pawl and ratchet mechanism, as occurs in the prior application. 90

As shown in the above referred to application the records are supported upon a table 51. This table is driven by means of a motor 59 which is secured to a collar 60. A pin 61 extends through the collar and engages a slot 62 in a sleeve 63. The upper end of the sleeve 63 is enlarged at 64 and supports the record table 51. The sleeve 63 rests upon a spring 65 so as to maintain the sleeve in friction driving contact with the record table. The slot in the sleeve permits the necessary vertical movement of the record table for changing records. 100 110 115 120 125 130

Furthermore, since the friction sleeve 52 always slides up on the spindle a distance exactly equal to a record or records, upon returning, it positions the top of the record to be played at exactly the same level in the playing position each time. Variation in the thickness of records will not affect the position of the record table.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

1. In a phonograph for playing a plurality of records in succession, means for changing the records comprising a record table, a spindle supporting said table, means for raising and lowering the said spindle, the said means having frictional engagement only with the spindle, substantially as set forth.

2. In a talking machine having a rotating record base, a motor for driving the record base, and a tone arm, means for supporting a set of inactive records, means for shifting a record from the record base to the inactive set, including a rotary cylindrical element having a cam track, a spindle for supporting the record base, a sleeve frictionally held on said spindle and means on said sleeve engageable with the said cam to raise and lower the record base upon rotation of the said cylindrical element, substantially as set forth.

3. In a talking machine having a rotating record base, a spindle for supporting the same, means for supporting a stack of inactive records above the record base, means for changing the records comprising a cam, a sleeve on the said spindle, said sleeve being movable by the said cam, and means on the sleeve for causing it to frictionally engage the said spindle to support the stack of records, substantially as set forth.

4. In a talking machine having a record table, and a motor for driving the same, means for changing the records comprising a spindle secured to and depending from the record table, a sleeve on said spindle and having frictional engagement therewith, and means for raising and lowering the sleeve to raise and lower the record table, substantially as set forth.

5. In a talking machine having a record table, and a motor for driving the same, means for changing the records comprising a spindle secured to and depending from the record table, a sleeve on said spindle and having frictional engagement therewith, means for raising and lowering the sleeve to raise and lower the record table, stop means above said table to limit the upward movement of

the table by a distance equal to the thickness of a record the said sleeve sliding up the said spindle a distance equal to the said thickness, whereby upon returning the top to the record is always positioned at the same playing level, substantially as set forth.

6. In a talking machine having a record table, and a motor for driving the same, means for changing the records comprising a spindle secured to and depending from the record table, a sleeve on said spindle and having frictional engagement therewith, means for raising and lowering the sleeve to raise and lower the record table, stop means above said table to limit the upward movement of the table by a distance equal to the thickness of a record the said sleeve sliding up the said spindle a distance equal to the said thickness, whereby upon returning the top of the record is always positioned at the same playing level, and a stop to limit the downward movement of the spindle the said stop causing the sleeve to slide down the spindle a distance equal to that which it moved up to record taking position, substantially as set forth.

In witness whereof, I have hereunto set my hand at Waynesboro, Pennsylvania, this 6th day of April, A. D. nineteen hundred and twenty-nine.

W. R. MOORE, Jr.
